UNITED STATES PATENT OFFICE.

ALBERT L. WATSON, OF PENN YAN, NEW YORK.

STAPLING HEAD.

Application filed August 9, 1920. Serial No. 402,172.

To all whom it may concern:

Be it known that I, ALBERT L. WATSON, a citizen of the United States, residing at Penn Yan, in the county of Yates and State 5 of New York, have invented a new and useful Stapling Head, of which the following is a specification.

This invention relates to staple forming machines, and it is the primary object of 10 the invention to provide a machine of this character which will form a staple and set the same in the material in which the staple is to be applied, by a single operation of the operating lever.

15 A further object of the invention is to provide means for automatically operating the forming block, simultaneously with the downward movement of the staple moving plunger.

20 A still further object of the invention is to provide a reciprocating plunger housing and a reciprocating plunger operating within the housing, together with means for disengaging the plunger housing and plunger automatically to permit the plunger to form a staple.

Another object of the invention is to accomplish the feeding of the wire of which 30 the staple is formed, to the forming block, simultaneously with the return stroke of the operating lever.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made 40 within the scope of what is claimed, without departing from the spirit of the invention.

Referring to the drawings:—

Figure 1 illustrates a front elevational view of a staple forming machine constructed in accordance with the present invention.

Figure 2 illustrates a sectional view taken on line 2—2 of Figure 1.

Figure 3 illustrates a detail view partly 50 in section of the forming block controlling lever.

Figure 4 illustrates a fragmental front elevational view of the plunger and plunger housing.

55 Figure 5 illustrates a detail view of one of the movable arms which connects the

plunger housing and plunger operating therein.

Figure 6 illustrates a detail view of the feeding rollers. 60

Figure 7 illustrates a fragmental sectional view disclosing the means for securing the feeding tube to the body portion.

Figure 8 illustrates a side elevational view 65 of the means for operating the feeding rollers.

Figure 9 illustrates a plan view of the roller operating pawls.

Figure 10 illustrates a front elevational view of the feeding rollers, and 70

Figure 11 illustrates a fragmental side elevational view disclosing the means for causing the operation of the feed roller operating rod.

Referring to the drawings in detail, the 75 reference character 5 designates the body of the machine which is connected to the support 6 and base 7, by means of the bolts 8 which have suitable connection with the support 6 through openings formed therein. 80

The body 5 includes a pair of spaced bars 9 and 10, to which are secured on opposite surfaces thereof, the plates 11, forming guide-ways for the movable carriage 12 which supports the movable elements of the 85 machine, the movable carriage being constructed to operate in the guide-ways to cause the operation of the machine.

Having connection with the carriage arm 12, is a reciprocating hollow plunger 13 90 which carries the cam member 14, on the outer front surface thereof, for purposes to be hereinafter more fully described, and in which housing is movably supported the reciprocating staple former 15, which includes 95 a relatively long rod 15' formed with a threaded portion to be fitted in the hollow plunger 13, the upper end of the rod terminating at a point above the upper end of the body 5, the upper end of the rod 15' being threaded as at 16 to permit of adjustment of the former 15' with relation to the hollow plunger.

The horizontal arms 17 have rigid connection with the reciprocating hollow plunger 105 13 adjacent the upper end thereof, the arms extending laterally therefrom and as shown these arms are apertured as at 18 to accommodate the lower ends of the coiled springs 19 which have their upper ends positioned in 110 suitable openings formed in the transversely extending arm 20 which is provided with a

central opening accommodating the operating rod of the former 15', the arms 20 being adjustably supported on the former 15' by contact with the sleeve 21. Operating on the 5 threaded end of the rod 15, is a lever 22 which may be rotated to adjust the rod 15 and former 15' longitudinally of the body of the machine. From the foregoing it is obvious that by rotating the lever 22, the arm 10 20 may be moved or adjusted with relation to the former 15'.

Enlarged bearings 23 form a part of the arm 20 and these bearings accommodate the upper ends of the connecting arms 24 which 15 are disposed on opposite sides of the reciprocating hollow plunger 13, and are adapted to move in the bearings, the lower ends of the connecting arms being provided with shoulders 25 see Figure 5 that engage under 20 the horizontal arms 17, for connecting the hollow plunger 13 and former 15'.

Supported between the upper end of the plunger 13, and the lower edge of the transversely extending arm 20, are the collars 26 25 and 27, the collar 27 having connection with the carriage 12 as at 27' for connecting the reciprocating hollow plunger 13, to the carriage 12, the coiled spring 29 being positioned between the upper end of the hollow 30 plunger 13 and the sleeve 27' for cushioning the connection between the hollow plunger 13 and bracket 28.

Cam members 30 are disposed on opposite sides of the reciprocating housing 13, the cam 35 members having connection with the spaced bars 9 and 10 by means of the brackets 31 which extend laterally from the spaced bars 9 and 10 so that the cam members will lie in the path of travel of the connecting arms 40 24 when the plunger 13 is moved downwardly in the forming of a staple. With this downward movement of the plunger 13, the lower ends of the connecting arms 24 move over the cam members 30 to disengage the 45 arms 24 from the horizontal arms 17 so that further movement of the operating lever will cause the staple former 15' to remain stationary while the plunger 13 moves thereover against the tension of the coiled springs 19.

50 Spaced brackets 32 are supported by the bar 10, and each of these brackets is provided with a bearing 33 through which operates the wire feeding roller operating rod 34, the lower end of which has connection with the bell crank lever 35, the upper end of which supports the pivoted pawls 36 which operate over the teeth 37 formed on the wire feeding roller 38.

The wire feeding roller 38 is provided 55 with an annular flange 39 operating between the annular flanges 30 of the wire feeding roller 31', which is also provided with teeth cooperating with the teeth 37 of the adjacent roller 38 so that movement of the roller 60 38 produces a relative movement of the roller

31' to cause the flange 39 to move between the flanges 30, resulting in the wire of which the staples are formed, being moved between the rollers and passed through to the forming mechanism of the machine.

An arm 40 is formed integral with the carriage 12 and is provided with a bearing in one end thereof adapted to accommodate the relatively short rod 41 which is rigidly connected to the operating rod 34, by means of 75 the bracket member 42. A coiled spring 43 is disposed between the arm 40 and the bracket 42 and provides means for connecting the arm 40 and bracket 42 to cause the upward movement of the operating rod 34 80 to move the pivoted pawls over the wire feeding roller 38 to accomplish the feeding of the wire material indicated at 44. It is of course obvious that upon the return movement of the operating rod 34, the pawls 36 85 are moved over the teeth 37, in an opposite direction to set the same for the next movement. In order that the upward movement of the operating rod 34 will be limited, a stop 45 is provided, the same being formed 90 on the operating rod and adapted to contact with the under surface of the bearing 33, when the operating rod 34 has reached the limit of its upward movement.

Supported at the lower end of the hollow 95 plunger 13, and carried by the former 15', is a forming head 46 which is grooved to provide a clearance for the hollow plunger 13 to permit the plunger 13 to move therethrough. The lower end of the forming head 100 is cut away as at 47, a bolt 48 being supported adjacent the cut away portion and on which bolt is supported the forming block 49 having an apertured ear 50 adapted to be embraced by the end 51 of the connecting 105 arm 52, the opposite end of said connecting arm 52 being supported between the arms 53.

Between the upper ends of the arms 53, is the roller 56 adapted to move over the cam 110 14 to cause the forming block 49 to swing inwardly or to a position within the path of travel of the former 15', the coiled spring 57 being provided which embraces the rod 58 that has connection with arm 54, so that the forming block will be automatically returned to its inoperative position, when the hollow plunger is moved downwardly to the mandrel 59, mounted on the base 7.

The lower end of the former 15' is slotted as at 60, and grooved on its under surface as 115 61, so that a wire may be moved in the grooved portion 61 and carried to a position in engagement with the mandrel 59. The slotted portion of the former 15' provides guideways for the finger 62 carried by 120 the lower end of the hollow plunger 13.

Extending through a lateral opening formed in the lower end of the forming head 46, is the wire feeding tube 63 held in such opening by means of the bolt 64 provided 125 130

with the notched portion 65, adapted to embrace one of the corners of the wire feeding tube 63, the nut 66 being provided to secure the bolt 64 against movement within the opening, in which the same is supported.

As shown, one edge of the wire feeding tube 63 is beveled as at 67 to cooperate with the beveled edge 68 of the staple former 15', so that when the staple forming plunger 10 moves downwardly, a length of wire which extends through the wire feeding tube 63 is severed at this point, whereupon the length of wire may be carried downwardly to the mandrel 59.

15 The operating means includes a lever 69 which has one end thereof pivotally connected to the support 6, as at 70, the lever 69 having connection with the carriage 12 through the medium of the connecting link 20 71 which has its lower end pivotally connected to the lever 69 as at 72, the upper end thereof having pivotal connection with the carriage 12 as at 73.

It might be further stated that the mandrel 59 is provided with a central rib to provide the camming surfaces 74, which cam surfaces move the ends of the length of wire forming a staple to clamp the same into engagement with the material to which the 30 staple is applied.

In order that a positive feed of the wire material 44, will be insured, the wire feeding roller 31' is formed with a groove to receive the wire, the roller being supported 35 by the lever 75 which has connection with the rod 76, forming a portion of the coiled spring 77, the upper end of the coiled spring 77 being anchored to the side bar 10 by means of the hook 78. It is therefore obvious that the tension of the coiled spring 40 77 tends to urge the arm 75 upwardly to move roller 31' into engagement with the wire feeding roller 38, and into contact with the wire being fed therebetween.

45 In the operation of the device, assuming that a length of wire has been severed, the former 15' connected to the lower end of the rod supporting the former 15', bends the severed length of wire about the former 50 block 49 to form the legs of a staple. The continued descent of the former and the driver operating the plunger 13 in unison, carries the cam surface 14 out of engagement with the roller 56, thus permitting the 55 spring to flex the toggle and thereby to withdraw the inside former block 49 from the path of the driver to the position shown in Figure 2 of the drawings. When the former 15' has substantially reached the po-

sition as shown in Figure 2 of the drawings, 60 the cam members 30 become effective to move the arms 24 to the position as shown in Figure 5 of the drawings, breaking the positive connection between the driver and former 15'.

65 The former 15' now remains stationary, while the driver continues to descend, forcing the staple through the material and clinching its legs against the anvils 59.

Having thus described the invention, what I claim as new is:—

1. In a staple forming machine, a body portion, a hollow plunger movable on the body portion, a former movable through the hollow plunger, a mandrel disposed under the plunger, a movable forming block pivotally supported adjacent to the mandrel, and adapted to move under the lower end of the hollow plunger, pivoted means 75 for supporting the forming block, and means carried by the movable plunger and cooperating with the pivoted formed supporting means for moving the former, under the hollow plunger, and means for delivering wire material to the mandrel.

2. In a staple forming machine, a body portion, a hollow plunger adapted to move on the body portion, arms pivotally carried by the hollow plunger, a roller carried by the arms, said arms being pivotally connected to the hollow plunger, a pivoted forming block at the lower end of the arm, a cam carried by the hollow plunger and adapted to move under the roller to cause the forming block to move under the hollow 95 plunger to bend a wire delivered to the lower end of the hollow plunger, and means for delivering wire.

3. In a staple forming machine, a body portion, a hollow plunger supported on the 100 body portion and adapted to move vertically with respect thereto, a former operating through the hollow plunger, a mandrel supported under the hollow plunger to cooperate therewith in the forming of a staple, 105 pivoted arms supported on the body portion and carrying a forming block at one end thereof, said forming block being pivoted to move under the hollow plunger, and means for delivering wire to the lower end 110 of the hollow plunger.

In testimony that I claim the foregoing as my own, I have hereto affixed my signature in the presence of two witnesses.

ALBERT L. WATSON.
